UNITED STATES PATENT OFFICE

LAWRENCE S. LAMB, OF DETROIT, MICHIGAN, ASSIGNOR TO HUDSON MOTOR CAR COMPANY, OF DETROIT, MICHIGAN, A CORPORATION OF MICHIGAN

METHOD AND APPARATUS FOR FORMING SHEET-METAL CHANNELS

Application filed December 28, 1927. Serial No. 243,018.

This invention relates to the shaping of sheet metal and particularly to the manufacture of window guide channels for metal automobile doors. It is an object of the invention to provide a method and suitable apparatus whereby sheet metal parts of this type may be manufactured in a rapid and efficient manner and in quantity production.

Before explaining in detail the present invention, and the method or mode of operation embodied therein, it is to be understood that the invention is not limited in its application to the details of construction and arrangement of parts illustrated in the accompanying drawings, since the invention is capable of other embodiments and of being practised or carried out in various ways. Also it is to be understood that the phraseology or terminology employed herein is for the purpose of description and not of limitation, and it is not intended to limit the invention beyond the terms of the several claims hereto appended or the requirements of the prior art.

The invention will be more clearly understood from the following description in conjunction with the accompanying drawings: in which,

Fig. 1 is a plan view of the upper half of an apparatus employed for shaping a suitable blank to channel form and leave a flange extending from one of the legs.

Fig. 2 is a plan view of the lower half of the apparatus.

Figs. 3 and 4 are sectional views taken upon the lines 3—3, of Fig. 2, showing the relation of the parts at the beginning and end of the shaping operations respectively.

Figs. 5, 6 and 7 are sectional views taken upon the lines 5—5, 6—6, 7—7, respectively of Fig. 2.

Fig. 8 is a plan view of the upper half of the apparatus for offsetting the flange extending from one of the legs of the channel.

Fig. 9 is a plan view of the lower half of this apparatus.

Figs. 10 and 11 are sectional views taken upon the line 10—10 of Fig. 9 showing the relation of the parts when the dies are separated to receive the work and at the begin-

ning of the shaping operation respectively.

Fig. 12 is a sectional view taken upon the line 10—10 of Fig. 9 showing the relation of the parts when the work has been completed.

Fig. 13 is a fragmentary sectional view taken upon the line 13—13 of Fig. 9.

Fig. 14 is a fragmentary sectional view taken upon the line 14—14, Fig. 9.

Fig. 15 is a plan view of a blank.

Figs. 16 and 17 are perspective and side elevational views respectively of the finished article; and

Fig. 18 is a fragmentary sectional view showing the assembly of the window guide channel of the invention in a metal automobile door.

The invention is particularly directed to the shaping of sheet metal blanks to produce window guide channels for metal automobile doors of the type illustrated in Fig. 18 comprising door pillars 10 to which a sheet metal panel 11 is suitably secured. A window guide channel 12 is secured to the pillar 10 by rivets 13 passing through a portion of the pillar and through the offset flange 14 of the guide channel and is reinforced by brackets 15 secured at one end to the base of the channel by rivets 16 and at the other end to the pillar by rivets 17.

In the practice of the invention a suitable blank 20 (Fig. 15) is shaped to channel form in a suitable apparatus comprising, as illustrated in Figs. 1 to 7, a base 21 having a hardened wearing block 22 secured to its top surface in any suitable manner as by bolts 23. The block 22 is provided with suitable elongated openings 24 positioned above recesses 25 in the base to receive for sliding engagement therewith blocks 26 having shoulders 27 adapted to engage the bottom surface of the block 22. The blocks 26 normally are held against the bottom surface of the blocks 22 by springs 31 extending between the bottom surface of the blocks 26 and the bottom of the recesses 25.

A ram 33 is mounted for movement towards and from the base 21 and for this purpose is provided with suitable openings

34 for bearing collars 35 which receive for sliding engagement therewith guides 36 suitably secured in the base. The ram 33 is provided with a central depending projection 38 to the sides of which suitable wearing blocks or die members 40 are secured in any suitable manner as by bolts 41. The lower portion of the die members 40 are shaped to cooperate with the yieldingly 5 mounted blocks 26 and openings 24 to shape the blank to channel form. In the form illustrated, the lower surface of the members 40 are provided with depending projections 46 which are adapted to form depressions 47 (Figs. 16 and 17) in the shaped channel to provide clearance for the heads of the rivets 16. Suitable strippers 42 are secured at spaced intervals along the top surface of the base and are adapted to engage a shaped 10 blank and remove it from the die members 40 as the ram 33 is raised. Plates 44 are secured at each end of the base as by bolts 45 and are cut away to serve for accurately 15 positioning a blank relative to the openings 24.

When the ram 33 is in raised position, the blanks 20 are placed between the positioning members 44 above the openings 24 in the block 22 or lower die member. The 20 ram 33 is then lowered to bring the upper die members 40 into engagement with the blanks and push the same against the yielding blocks 26 and into the openings 24 thereby shaping a portion of the blank to channel form with a flange 14^a extending from one of the legs of each channel. The ram is then raised and if the articles tend to stick to the die members 40, they will engage the strippers 42 and be removed therefrom.

40 The flanges 14^a are then offset a predetermined amount to form the flanges 14 of the completed guide channel. A suitable apparatus for this purpose (Figs. 8 to 13) 45 comprises a base 50 having hardened blocks 51 and 52 secured near the edges of the top surface in any suitable manner as by bolts 53. The blocks 51 and 52 constitute lower die members and are shaped to receive the 50 channel portions of the articles with the flange 14^a spaced from a portion thereof. A ram 55 is arranged for movement towards and from the base and with this in view is provided with openings 56 to receive guide 55 collars 57 for sliding engagement with guides 58 suitably secured in the base. Near opposite edges of the ram 55 and directly above the blocks 51 and 52 suitable work 60 engaging members 60 and 61 are movably secured by bolts 62 passing through openings 63 provided with shoulders 64 adapted to engage and serve as a stop for the head of the bolts thereby limiting the downward movement of the members 60 and 61. The 65 members 60 and 61 are normally held in

extended position by springs 65 extending between recesses 66 and 67 in the ram and blocks respectively. Suitable spaced L-shaped guides 70 are secured to the bottom surface of the ram by bolts 71 and are 70 adapted to engage suitable shoulders 72 upon upper die members 73 and 74 so that the latter may be free for movement relative to the ram in a direction perpendicular to the movement of the latter. A suitable block or 75 cam 75 is secured to the top surface of the base in any suitable manner as by bolts 76 and is adapted to engage the dies 73 and 74 to move the same apart. The outer lower 80 portions of the dies 73 and 74 are shaped to engage the flanges 14^a and to bend the same along a line 77 of previous fold and a line 78 spaced therefrom. In the form shown, the dies 73 and 74 are provided with projections 79 adapted to form depressions 80 in 85 the flanges 14 to provide clearance for bolts, rivets, or the like.

When the ram 55 is raised, the channel portion of the blanks are placed in the channel shaped depressions of the blocks 51 or 90 52. The ram is then moved downward thereby bringing the work engaging members 60 or 61 into yielding engagement with the channel portions of the blanks and holding the same firmly against members 51 or 95 52. Upon further downward movement of the ram, the inner surfaces of the dies 73 and 74 are brought into engagement with the cam 75 and are thereby moved outward. As a result, the die members 73 and 74 are 100 given a resultant movement inclined with respect to the flanges 14^a and the legs of the channel from which they extend. Thus, the dies 73 and 74 engage the flanges 14^a at 105 points spaced from the legs and while moving in such a direction first to bend each flange along the line of previous fold 77 and then press the same against the leg and top surface of the blocks 51 and 52 to form the offset flange 14.

110 What I claim is:

1. The method of making an automobile window guide channel which comprises bending a portion of a suitable metal blank to channel form with a flange extending from one of the legs, and without weakening the flange except at its line of fold, bending the flange along the line of previous bend, and thereafter bending the flange in the opposite direction along a line in the body of said flange spaced from said line of bend previously unweakened.

2. The method of making an automobile window guide channel which comprises shaping a portion of a suitable sheet metal blank to channel form with a flange extending from one of the legs, and thereafter offsetting the flange by the application of pressure thereto at a point spaced from said leg

and along a path inclined to said flange and leg.

3. In an apparatus for shaping sheet metal previously bent with a flange, the combination of a lower die for supporting the body of the sheet metal with the flange spaced therefrom, a ram movable towards and from said lower die, a member yieldingly mounted in said ram adapted to engage said body 10 and hold the same against said lower die, an upper die depending from and slidably mounted on the lower surface of said ram for movement in a direction perpendicular to said ram and adapted to engage said flange and fold one portion thereof against 15 said body and press another portion against said lower die, and a cam for moving said upper die relative to the ram as the latter moves toward the lower die.

20 In testimony whereof I affix my signature.
LAWRENCE S. LAMB.
